CALVIN COLT AND CHESTER H. COLT, OF JONESBOROUGH, TENNESSEE.

Design No. 4,087, dated May 31, 1870.

DESIGN FOR A MICA CHIMNEY FOR LAMPS.

The Schedule referred to in these Letters Patent and making part of the same.

To all whom it may concern:

Be it known that we, CALVIN COLT and CHESTER H. COLT, of Jonesborough, in the county of Washington and State of Tennessee, have invented a new and useful Design for Mica Chimneys for Lamps, of which the following is a full and exact description, reference being had to the accompanying drawing making part of this specification.

Our invention consists in a mica lamp-chimney, made in the form herein shown, which represents a sheet of mica, rolled into a cylindrical form, with its sides lapped and riveted with white-metal rivets and its top and bottom bound by metallic bands, the top band being bell-shaped, as shown,

What we claim as our invention, and desire to secure by Letters Patent, is—

The design for mica chimneys for lamps herein shown and described.

In testimony that we claim the foregoing design, we have hereunto set our hands this 5th day of November, 1869.

CALVIN COLT.
CHESTER H. COLT.
